HOIST MECHANISM

Francis I. Rataiczak, Dayton, Ohio, assignor to
General Motors Corporation, Dayton, Ohio, a
corporation of Delaware

Application March 12, 1945, Serial No. 582,215

5 Claims. (Cl. 254—97)

1

This invention relates to hoist mechanism and more particularly to an improved gun turret hoist for use in airplanes.

It is an object of this invention to provide a simple, compact and dependable hoist mechanism which may be used for hoisting gun turrets and the like.

It is a further object of this invention to provide a manually operated hoist which is easy to operate and which is capable of lifting substantial loads.

Another object of this invention is to provide improved safety mechanism for preventing too rapid lowering of the load.

Another object of this invention is to provide a safety device which automatically stops the lowering operation upon release of the operating handle by the operator.

More particularly, it is an object of this invention to provide a manually operated hoist in which a brake mechanism is used for preventing too rapid lowering of the load and in which an overrunning clutch is provided for rendering the brake ineffective when raising the load.

Further objects and advantages of the present invention will be apparent from the following description, reference being had to the accompanying drawings, wherein a preferred form of the present invention is clearly shown.

In the drawings:

Fig. 1 is a pictorial view showing the hoist mechanism;

Fig. 2 is a fragmentary sectional view (with parts broken away) taken substantially on line 2—2 of Fig. 3;

Fig. 3 is a sectional view taken on line 3—3 of Fig. 2;

Fig. 4 is a sectional view taken on line 4—4 of Fig. 3; and

Fig. 5 is a fragmentary sectional view showing a gear lock.

The hoist illustrated in the drawings was designed for raising and lowering a gun turret on an airplane, but it is obvious that hoists of the type shown may be used for other purposes equally well.

Referring now to the drawings wherein I have shown a preferred embodiment of my improved hoist mechanism, reference numeral 10 designates a stationary top support from which the hoist mechanism is suspended by means of suspension rods 12 and suspension cables 14. The support 10 may be any suitable support and in the case of an airplane would be a part of the fuselage of the plane. Reference numerals 16 and 18

5 designate stationary mounting plates between which the gear housing 20 is mounted as shown. Reference numeral 22 designates generally the movable portion of the hoist to which the load is secured. Thus when the hoist is used for raising and lowering a gun turret, the gun turret is attached directly to the movable portion 22 of the hoist. The guide rods 24 are attached to the movable portion 22 and serve as guide means for the portion 22 as it moves up and down. The rods 24 are slidably supported within bushings 26 carried by the plate 16 as shown. The upper ends of the rods 24 are bolted to the guide plate 28 which is supported for sliding engagement with the rods 12 and the central cylindrical housing 30.

Referring now to Figs. 2 and 3 of the drawings wherein I have shown the gear mechanism for operating the hoist, reference numeral 40 designates the handle or crank which is secured to the crank shaft 42 and disc 44 by means of a pin 46 arranged as shown in Fig. 3. The shaft 42 has a pinion 48 keyed thereto adjacent the inner end of the shaft which is arranged in meshing engagement with a larger gear 50. The gear 50 is keyed to the shaft 52 to which a pinion 54 is also keyed. The pinion 54 is arranged in driving engagement with a larger gear 56 which in turn is keyed to the extension 58 provided on a pinion gear 60. The pinion 60 is rotatably supported on the shaft 62 and is drivingly connected to a pair of gears 64 and 66 (see Fig. 2) which in turn are drivingly connected to the reciprocating rack 68. The shafts 42, 52 and 62 are suitably journaled in the complementary gear housing sections 70 and 72.

The reciprocating rack 68 is provided with a reduced lower end portion 76 which is threaded to receive the nut 78. The nut 78 secures the movable carriage or load supporting means 22 to the rack 68. The rack 68 is of semi-circular cross-section and is slidably supported within the stationary cylindrical housing 30 which in turn is secured to the main support 10 and the plates 16 and 18. Inasmuch as a gun turret hoist must be capable of raising and lowering a gun turret which when fully equipped weighs in the neighborhood of one ton, it is apparent that a large amount of force must be transmitted from the handle 40 to the rack 68 by the interposed gears. By virtue of using a pair of gears 64 and 66 for transmitting power from the gear 60 to the rack 68, the load on the individual teeth on the gears 60, 64, 66 and 68 has been reduced.

55 A novel brake and brake release mechanism has

been provided for holding the load in any desired position and for preventing the hoist from lowering the gun turret when one lets go of the handle 40. The brake shoe mechanism comprises a pair of brake shoes 100 which are pivotally supported on the end plate 72 of the gear housing by means of suitable studs 104 arranged as shown. The brake shoes 100 are provided with suitable brake lining material 106 which is arranged to frictionally engage the cylindrical brake drum 108 which is drivingly connected to the shaft 42 through an overrunning clutch. The overrunning clutch comprises the clutch plate 44 keyed to the shaft 42 and a plurality of frictional rollers 110 which are arranged to engage the internal surface 112 of the brake drum 108 when the handle is rotated in a direction so as to lower the hoist. As shown in Fig. 4, the frictional rollers 110 are biased into frictional engagement with the internal surface 112 by the spring pressed plungers 114. Each plunger 114 is slidably supported in a hole 116 provided in the clutch plate 44. A spring 118 is provided for each plunger for pushing the plunger outwardly. The arrangement of the overrunning clutch is such that the brake drum 108 revolves with the shaft 42 at all times upon rotation of the handle in the direction for lowering the load but does not rotate with the shaft 42 upon rotation of the handle in the opposite direction. By virtue of the above described arrangement, it is apparent that the handle may be rotated so as to elevate the gun turret even though the brake shoes 100 are in firm engagement with the brake drum 108. It is also apparent that the brake mechanism described hereinabove will hold the gun turret in any desired degree of elevation.

In order to lower the turret it is desirable to at least partially release the brake mechanism. This may be done by swinging the handle 40 about the pivot 46 in a plane at right angles to the normal plane of rotation of the handle 40. Movement of the handle 40 in this manner causes the handle projection 130 to push in on the brake operating plunger 132 slidably carried by the clutch plate 44. The plunger 132 is provided with a roller 134 at its inner end which cooperates with the circular groove 136 provided on the cone-shaped cam element 138 which is slidably supported on the shaft 42. The cone-shaped element 138 is arranged to engage the adjustable studs 140 carried by the brake shoe operating levers 142. The levers 142 are pivoted on pins 144 carried by the end plate 72 of the gear housing. The outer ends 146 of the levers 142 serve as cams for camming the brake shoes 100 into braking engagement with the brake drum 108. The inner end of each lever 142 is connected to one end of a spring 148 which has its other end connected to one of the brake shoes 100 in the manner shown. Thus by manipulating the handle 40 so as to push in on the plunger 132, the cone-shaped cam 138 operates the levers 142 to release the pressure on the brake shoes 100. The brakes preferably are adjusted so as never to become fully disengaged at any time whereby the amount of restraining force which needs be applied to the handle when the load is being lowered is less than otherwise would be required. As pointed out hereinabove, the overrunning clutch declutches the brake from the crank shaft 42 when the handle 40 is rotated in the direction for raising the turret. As a consequence of the above arrangement, the brake does not interfere with free movement of the hoist during the

raising operation even though the brake at all times restricts the movement of the hoist when the load is being lowered. If desired, the studs 140 may be adjusted to cause the cam 138 to completely disengage the brake shoes 100 from the drum 108.

A gear lock generally designated by the reference numeral 150 (see Fig. 5) has been provided for positively locking the gears against rotation. The gear lock comprises a reciprocating locking plunger 152 which is adapted to engage with an aperture 154 in the gear 50 for positively locking the gear 50 and consequently the rest of the gear train against rotation. A spring 157 biases the plunger 152 inwardly at all times and a pin 156 carried by the plunger is provided for holding the plunger outwardly. The pin 156 rests within a deep notch 158 when the gears are locked against rotation and is held within a shallow notch 160 when the plunger is out of locking engagement with the gears.

While the form of embodiment of the invention as herein disclosed, constitutes a preferred form, it is to be understood that other forms might be adopted, as may come within the scope of the claims which follow.

What is claimed is as follows:

1. In a hoist mechanism, a crank shaft for said hoist, a support for said crank shaft, brake shoes pivotally carried by said support, a brake drum surrounding said shaft, a one-way clutch drivingly connecting said brake drum to said shaft, cam means slidably supported on said shaft, complementary cam means for camming said brake shoes into engagement with said brake drum, a crank for operating said shaft, and means carried by said crank for operating said cam means so as to cause said brake shoes to at least partially disengage said brake drum.

2. In a power unit, a drive shaft, a support for said shaft, brake shoes pivotally carried by said support, a brake drum surrounding said shaft, a one-way clutch drivingly connecting said brake drum to said shaft, cam means slidably supported on said shaft, complementary cam means for camming said brake shoes into engagement with said brake drum, a crank for operating said shaft, and means carried by said crank for operating said cam means so as to cause said brake shoes to partially disengage said brake drum, said clutch and said brake operating means being so constructed and arranged whereby said crank shaft is free to rotate in the one direction of rotation unhampered by said brake shoes but is prevented from freely rotating in the opposite direction.

3. In a hoist, a support, a movable element, means including a gear train for raising and lowering said movable element relative to said support, said gear train including a shaft, a rotatable handle mounted on said shaft for operating said gear train, said handle being so mounted on said shaft as to be tiltable in a direction other than the normal plane of rotation thereof, brake mechanism including a drum for holding said movable element in any given position, a clutch between said shaft and said brake drum, said clutch permitting relative movement of the shaft and the brake drum when the shaft is rotated to raise the movable element and causing the shaft and brake drum to rotate as a unit when the movable element is lowered, and means operated in response to tilting of said handle for rendering said brake mechanism ineffective.

4. In a hoist, a support, a movable element,

mechanism for raising and lowering said movable element relative to said support including a shaft, a rotatable handle pivotally mounted upon said shaft for operating said mechanism, means including a brake for holding said movable element in any given position, power transmitting means between said brake and the shaft, said power transmitting means including an overrunning clutch whereby operation of said mechanism in one direction disconnects said brake means from said mechanism, and means operated in response to tilting of said handle about its pivotal mounting in a direction at right angles to the normal plane of rotation thereof for rendering said brake means ineffective during operation of said mechanism in the opposite direction.

5. In a hoist mechanism, a rotatable crank-shaft for said hoist, a support for said crank-shaft, brake shoes pivotally carried by said support, a brake drum surrounding said shaft, a one-way clutch drivingly connecting said brake drum to said shaft, cam means slidably supported on said shaft, complementary cam means for moving said brake shoes into engagement with said brake drum, a crank for rotating said shaft, said

10

crank being pivotally mounted on said shaft for movement in a direction at right angles to the normal plane of rotation thereof, and means actuated by movement of said crank about its pivotal mounting on said shaft for operating said cam means, said complementary cam means and said brake shoes.
